UNITED STATES PATENT OFFICE.

FRANKLIN K. YOUNG, OF BOSTON, MASSACHUSETTS.

FIREARM.

SPECIFICATION forming part of Letters Patent No. 764,513, dated July 5, 1904.
Application filed October 10, 1902. Serial No. 126,731. (No model.)*To all whom it may concern:*

Be it known that I, FRANKLIN K. YOUNG, a citizen of the United States, and a resident of Boston, in the county of Suffolk and State of Massachusetts, have invented certain new and useful Improvements in Firearms, of which the following is a specification.

The invention relates to improvements in the breech mechanism of firearms.

One object of the invention is to provide means for automatically locking the bolt before the cartridge is exploded and automatically unlocking the bolt after the explosion.

Another object of the invention is to provide a guide and support for the bolt when the bolt is thrown back after firing.

Another object of the invention is to provide means for automatically returning the bolt to the firing position after it has been thrown back.

The invention is especially adapted for use in firearms in which the initial movement of the breech mechanism after firing is the rearward movement of the firing-pin actuated by the explosion before movement of the bolt; but it is not in all of its features exclusively limited to that class of firearms.

The invention consists in the several novel features which will be fully described herein and which will be particularly pointed out in the claims at the close of the specification.

In the drawings, Figure 1 is a plan of a breech mechanism of a firearm embodying the invention, showing the parts when in position for firing. Fig. 2 is a plan showing the position at the time of explosion. Fig. 3 is a plan showing the position when thrown part way back after the firing. Fig. 4 is a plan showing the position when thrown clear back after the firing. Fig. 5 is a partial side elevation of Fig. 2 with the front end of the casing broken away to show the locking of the bolt by projections on the bolt engaging with shoulders on the casing. Fig. 6 is a side elevation partly in section, of Fig. 1. Fig. 7 is a side elevation, partly in section, of Fig. 3. Fig. 8 is a cross-section through the bolt on line 8-8 of Fig. 7, showing the front stop for the spring. Fig. 9 is a cross-section on line 9-9 of Fig. 7, showing the rear stop for the

spring. Fig. 10 is a bottom view of a portion of the bolt, showing the guide-slot. Fig. 11 is a detail plan view of the firing-pin. Fig. 12 is a detail side elevation of the firing-pin. Fig. 13 is a cross-section on line 13-13 of Fig. 12. Fig. 14 is a cross-section on line 14-14 of Fig. 12. Fig. 15 is a cross-section on line 15-15 of Fig. 12. Fig. 16 is a detail side elevation, and Fig. 17 is an end elevation, of the ring 17 when in the position shown in Figs. 6 and 7. Fig. 18 is a side elevation, and Fig. 19 is an end elevation, of the fid 19. Fig. 20 is a cross-section on line 20-20 of Fig. 21, showing the yoke. Fig. 21 is a side elevation, partly in section, showing the rear part of the bolt and firing-pin and connections. Fig. 22 is a plan view, partly in section, showing the firing-pin and its rear-end connections.

Referring now to the drawings, 1 is the breech portion of a gun-stock, partially broken away. 2 is the bolt-casing, 3 the bolt, and 4 the firing-pin, which is held and carried in the bolt. The bolt has a longitudinal movement within the casing 2, and the firing-pin has a longitudinal movement within the bolt. The bolt also has a partially rotary movement imparted to it by the longitudinal movement of the firing-pin, as will be hereinafter described. 5 is the magazine, which, however, forms no part of this invention.

In order to guide and steady the bolt in its longitudinal movement, the rearward extension 6 of the casing is formed with guideways 7, in which slide the flanges 8 on the yoke 9 at the rear of the bolt. (See Figs. 3, 4, 7, 8, 19 and 20.) The yoke 9 is connected with the bolt 3 by a male and female thread, so that in the longitudinal movement of the bolt the yoke 9 will be carried with it without interfering with the partial rotary movement of the bolt. (See Fig. 21.) It is not intended to limit the guide and way to the particular form of construction shown, as it is obvious that the form may be varied.

Surrounding the firing-pin 4 is a coil-spring 12, the forward end of which butts against an abutment which is fast to the firing-pin, and the rear end of which butts against an abutment which is not fast to the firing-pin, so that when the firing-pin moves rearwardly

with relation to the bolt the spring will be compressed. The rear abutment, as illustrated in the drawings, consists of a ring 13, through which the firing-pin passes loosely. The ring 13 has a neck 14, which passes through a slot 15 in the side of the bolt, and a head 16, which lies on the outside of the bolt. The slot 15 is slightly elongated, so as to permit a short longitudinal movement of the ring 13; but the spring 12 will normally hold the ring 13 in its most rearward position. The forward abutment consists of a ring 17, which is made fast to the firing-pin and has a stud 18, which enters an elongated camway or slot in the side of the bolt. (See Fig. 10.) The method shown of fastening the ring 17 to the firing-pin is as follows: The forward portion of the firing-pin which moves in the perforated head of the bolt is cylindrical, as shown in Figs. 11, 12, and 15. Back of this cylindrical portion the pin has a short portion 40, which is oblong in cross-section, as shown in Fig. 14, the shorter diameter being the same as the diameter of the cylindrical portion. Back of the said 5 oblong portion 40 there is a short cylindrical portion 41 and back of that there is another portion 42 also oblong in cross-section like the oblong portion 40, thus forming notches 46 between the two oblong portions on two sides. The ring 17 is formed with an oblong opening 43 (see Fig. 17) of the right form and size to slip over the oblong portion of the firing-pin and will therefore, of course, pass over the cylindrical portion. The ring is 10 passed over the cylindrical end of the firing-pin and moved back until it passes the oblong portion 40 as far as the short cylindrical portion 41 between the two oblong portions 40 and 42. The ring is then given a quarter- 15 turn, bringing the oblong opening in the ring at right angles to the oblong section of the firing-pin and bringing the sides of said oblong opening into the notches 46 in the firing-pin. When in this position, the ring 17 will 20 engage with the sides of the notches, and therefore cannot be moved forward or back. In order to hold the ring in this position, the fid 19, having an oblong hole 44 similar to that in the ring and provided with fingers 20, (see Figs. 18 and 19,) is slipped on over the cylindrical end of the firing-pin and back onto the oblong sectional part 40, with the fingers 20 extending through the oblong opening 43 in the ring 17 on opposite sides of the cylindrical portion 41 and wedging it in its position, thus preventing the ring from turning or from endwise movement. The cam-path in the bolt in which the stud 18 moves is formed with a longitudinal forward portion 21, a diagonal middle portion 22, and an enlarged rear portion 23, having a notch 24, which forms a seat for the stud 18 during the rearward movement of the bolt after the firing-pin has made its initial rearward movement and during the forward movement of 25

the bolt until the stud is thrown out in the manner to be hereinafter described. If the firing-pin be moved forward or back relative to the bolt, it is apparent that when the stud 18 passes through the diagonal portion 22 of 70 the cam-path as the firing-pin is incapable of rotary movement the bolt which is free to turn will be given a partial turn. At the forward end of the bolt are one or more lugs or projections 25, which when the bolt is in its most 75 forward position, as it will be when ready for firing, will engage with the shoulders 26 inside of the casing 2, thereby preventing the bolt from moving rearwardly until the bolt is turned to disengage the projections 25 from 80 the shoulders 26. (See Figs. 5 and 6.) This turning of the bolt and consequent disengagement cannot take place until the firing-pin moves rearwardly first through the straight portion 21 of the cam-path and then through 85 the diagonal portion 22.

Projecting up through the bottom of the rear extension 6 of the casing is a stop 27, which when the bolt 3 is thrown rearward engages the head 16 of the ring 13, which 90 forms the rear abutment of the spring 12. It is apparent that if the bolt be thrown back so as to cause the head 16 to strike the stop 27 with force, said head 16 and the ring-abutment 13 being capable of movement as already explained, it will compress spring 12, and when the rearward movement of the bolt is finished the expansion of the spring will cause the bolt to rebound forward. The stop 27 is preferably mounted on a spring-seat 28, 100 so that by depressing the spring, as can be done from outside by hand, the stop 27 will be dropped, thereby enabling the bolt to be entirely withdrawn, if desired for any reason. After the cartridge is exploded the force of 105 the gas thus generated will first drive the firing-pin violently backward without rearward movement of the bolt until the bolt is turned by the passage of the stud 18 through the diagonal portion of the cam-slot, as already 110 explained. The impulse thus given to the firing-pin will carry it far enough to bring the stud 18 up into the enlarged portion of the cam-path, and then the spring 12, which has thus become tense, will throw the firing-pin slightly forward again until the stud 18 115 drops into the notch 24, and thus locks the firing-pin in relation to the bolt until the stud becomes disengaged from the notch, as will be hereinafter described. As soon as the retraction of the firing-pin has turned the bolt to disengage the lugs 25 from the shoulders 26 inside of the casing the bolt 3 will also be driven rearwardly, causing the head 16 to strike the stop 27 with force, compressing the 120 spring 12 still farther, as already explained, and thereby causing the bolt to rebound forward with force.

The yoke 9 is cloven on the under side, forming the two flanges 8. Fast on the rear 125 130

er 1 of the firing-pin and forming a part thereof is a sleeve 45, having on the under side a lug 29, which extends downwardly and forwardly between the flanges 8. The method 5 of attaching the sleeve 45 to the firing-pin is not claimed as new, and therefore is not specifically described. A hand-piece and collar 47 on the rear end is convenient for hand manipulation.

10 The catch 30 of the trigger 31 projects up through the bottom of the rear extension 6 of the bolt-casing and is engaged by the lug 29 on the rebound of the bolt after being thrown rearward by the explosion, and thus 15 stops the forward movement of the firing-pin until released by the pull of the trigger.

On the upper side of the bolt 3 is a projection 32, which when the lug 29 engages with the trigger-catch 30 in the forward movement 20 of the bolt engages with the cam portion 33 of the bolt-casing. The effect of this engagement, however, is not to immediately stop the forward movement of the bolt. The projection 32 will ride down on the inclined cam 25 edge 33 and part way down the square end beyond the incline, and the bolt 3 will continue to move forward a short distance, as allowed by the cam 33, after the firing-pin is brought to a stop by the trigger-catch 30. At the 30 same time the cam action will give the bolt a partial turn. This forward action of the bolt after the firing-pin is brought to a stop will carry the notched portion 24 of the cam-path away from the stud 18, and the turning action 35 of the bolt will bring it around so as to bring the entrance to the diagonal portion of the cam-path in line with the stud 18. (See Fig. 10.) The firing-pin will thus be permitted to move forward without impediment when the 40 trigger is pulled to release the catch 30 from the lug 29, which forms a part of the firing-pin. Although the bolt has completed its forward movement, it has not yet turned its full extent and will not do this until the firing- 45 pin moves forward and carries the stud 18 through the diagonal portion of the cam-slot, and this cannot occur until the trigger is pulled. The projections or lugs 25 on the forward end of the bolt are, however, in position, so that when the bolt does complete its 50 turning the said projections will be brought around in front of the shoulders 26 to lock the bolt against retraction during the movement of the firing-pin through the cam-path after 55 the discharge, as already described. The spring 12 during all this time is under tension, and as soon as the trigger 31 is pulled to release the catch 30 from the firing-pin the spring will throw the firing-pin forward with 60 violence and cause it to explode the cartridge, the bolt being in the meantime given the completion of its turning movement and locking the bolt against retraction. The explosion 65 will throw the firing-pin again to the rear, then unlock the bolt, and throw it rearwardly

and then forward again to bring the firing-pin again into position to be thrown forward by the spring 12 without impediment when the trigger is pulled, in the manner already described.

70 While the cam-path is shown as extending through the wall of the bolt, it is obvious that it may be either a groove or any other form of guideway. It is also obvious that the cam-path and stud may be either single or double, 75 also that the cam-path may be formed in the firing-pin and the stud may project from the bolt, and still be within the scope of my invention. The essential feature is that there should be a connection which will turn the 80 bolt, so as to lock and unlock it at the proper time.

The firearm herein described is especially adapted for use with a cartridge such as shown in United States Letters Patent No. 85 624,146, granted to me May 2, 1899, but is not intended to be limited to use with that particular form of cartridge.

It is obvious that any form of casing may be attached for protecting the hand and face 90 of the user of the gun against the bolt when moving rearward.

What I claim is—

1. In breech mechanism for firearms, a bolt, a firing-pin carried in the bolt, a coil-spring 95 surrounding the firing-pin, a front abutment for said spring attached to the firing-pin, a rear abutment for said spring carried by the bolt, said bolt being capable of a limited movement longitudinally with relation to said rear 100 abutment, a stop which engages said rear abutment when the bolt is thrown rearward and permits rearward movement of the bolt relative to the spring, thereby compressing the spring so that the spring will throw the 105 bolt forward again, substantially as described.

2. In breech mechanism for firearms, a bolt, a firing-pin carried in the bolt, a coil-spring surrounding the firing-pin, a front abutment for said spring attached to the firing-pin, a 110 rear abutment for said spring carried by the bolt, a slot in said bolt and a lug projecting from said rear abutment through said slot, said slot being elongated whereby the bolt is permitted a longitudinal movement relative 115 to the rear abutment, and a stop which engages with the lug on said rear abutment when the bolt is thrown rearward thereby compressing the said spring so that the spring will throw the bolt forward again, substantially as 120 described.

3. In breech mechanism for firearms, a bolt, a firing-pin carried in said bolt and movable longitudinally therein, means for preventing rotation of the firing-pin during its longitudinal movement in the bolt, a coil-spring surrounding the firing-pin, a front abutment for said spring attached to the firing-pin, a rear 125 abutment for said spring carried by the bolt, said bolt being capable of a limited movement 130

longitudinally with relation to said rear abutment, a detent for the bolt in its forward position to prevent longitudinal movement, connections between the firing-pin and bolt actuated by the movement of the firing-pin to partially rotate said bolt before the firing-pin completes its forward movement to the cartridge, and causes the engagement of the bolt with said detent and which rotates the bolt 5 in the reverse direction during the rearward movement of the firing-pin, and releases the detent after the firing-pin has partially completed its rearward movement permitting the bolt to move rearwardly under the force of the explosion, a stop which engages the rear abutment of said spring before the bolt 15 completes the rearward movement, thereby compressing said spring and causing the bolt to rebound, and a trigger which engages the firing-pin and stops its forward movement, substantially as described.

4. In breech mechanism for firearms, a bolt, a firing-pin carried in said bolt and movable longitudinally therein, means for preventing 20 rotation of the firing-pin during its longitudinal movement in the bolt, a coil-spring surrounding the firing-pin, a front abutment for said spring attached to the firing-pin, a rear abutment for said spring carried by the bolt, 25 said bolt being capable of a limited longitudinal movement relative to said rear abutment, a detent for the bolt in its forward position to prevent longitudinal movement, a cam connection between the firing-pin and bolt actuated by the movement of the firing-pin which 30 partially rotates said bolt before the firing-pin completes its forward movement to the cartridge and causes the engagement of the bolt with said detent and which rotates the bolt in the reverse direction during the rearward movement of the firing-pin and releases it from 35 the detent after the firing-pin has partially completed its rearward movement, permitting the bolt to be moved rearwardly by the force of the explosion, a stop which engages the 40 rear abutment of said spring before the bolt completes its rearward movement, thereby compressing said spring and causing the bolt to rebound, a safety-detent in the bolt which 45 is brought into position by the rearward and turning movement of the bolt and prevents forward movement of the firing-pin, a cam which is engaged by the bolt on the rebound and turns the bolt to disengage said detent 50 from the firing-pin, and a trigger which engages the firing-pin, substantially as described.

5. In breech mechanism for firearms, a bolt, a firing-pin, mechanism which causes the bolt to partially rotate when it is driven back after 55 firing, mechanism which causes the bolt to partially rebound after it has been driven rearwardly, a safety-detent on the bolt which is

brought into operative position by the rearward and turning movement of the bolt and prevents forward movement of the firing-pin, 65 and a cam which is engaged by the bolt on the rebound and turns the bolt and disengages the safety-detent, substantially as described.

6. In breech mechanism for firearms, a casing, a bolt which is both slidable and rotatable, a firing-pin which is slidable within said bolt, a coil-spring surrounding said firing-pin, a fixed abutment on said firing-pin for the forward end of said spring, a rear abutment for said spring mounted in said bolt, the bolt being capable of a limited movement relative to said rear abutment, a projection on said rear abutment which extends through an elongated slot in the side of said bolt, and a stop on the casing which engages the projection on the said rear abutment and stops it while the bolt is free to move farther rearward, substantially as described.

7. In breech mechanism for firearms, a rotatable bolt, a firing-pin carried in said bolt, a projecting lug on said firing-pin, a guideway in which said lug moves when the firing-pin moves whereby the firing-pin is prevented from rotation, a stud on said firing-pin which engages with a cam-slot in said bolt 90 whereby the rearward movement of the firing-pin in said bolt turns the bolt, a notch in said cam-slot and a spring which is compressed by the rearward movement of the firing-pin and throws the firing-pin forward 95 far enough to engage said stud with said notch, means for throwing the bolt forward again, a projection on the bolt which engages a cam portion of the casing and moves the bolt in such way as to disengage said notch from the firing-pin and a trigger which prevents full forward movement of the firing-pin until the trigger is pulled, substantially as described.

8. In breech mechanism for firearms, a rotatable bolt and a receiver therefor, a firing-pin in said bolt movable therein, a projection on the firing-pin which moves in a fixed guideway when the firing-pin moves and prevents rotation of said firing-pin, cam connections between the firing-pin and bolt whereby the movement of the firing-pin causes the bolt to turn, mechanism which stops the firing-pin in its rearward movement before the bolt stops, and cam connections between the bolt 100 and receiver which partially turn the bolt during the rebound of the bolt, substantially as described.

In testimony whereof I have affixed my signature in presence of two witnesses.

FRANKLIN K. YOUNG.
